UNITED STATES PATENT OFFICE

JOHN J. GUND, OF CLEVELAND, OHIO, ASSIGNOR TO LAKEWOOD STORAGE, INC., OF LAKEWOOD, OHIO, A CORPORATION OF OHIO

DESIGN FOR A COMBINED TRACTOR AND TRAILER

Application filed February 20, 1930. Serial No. 34,598. Term of patent 14 years.

To all whom it may concern:

Be it known that I, JOHN J. GUND, a citizen of the United States, residing at Cleveland, in the county of Cuyahoga and State of Ohio, have invented a new, original, and ornamental Design for Combined Tractor and Trailer, of which the following is a specification, referring had to the accompanying drawing, forming part hereof.

the combined tractor and trailer showing my new design; and

Fig. 2 is a side elevation of the combined tractor and trailer shown in Figure 1.

I claim:

The ornamental design for a combined tractor and trailer as shown.

JOHN J. GUND.
